R. BELCHER,
ADJUSTABLE GUSSET FOR ENVELOPS,
APPLICATION FILED JULY 27, 1918.

1,304,145.

Patented May 20, 1919.

UNITED STATES PATENT OFFICE.

RUDOLPH BELCHER, OF CHICAGO, ILLINOIS.

ADJUSTABLE GUSSET FOR ENVELOPS.

1,304,145.

Specification of Letters Patent. Patented May 20, 1919.

Application filed July 27, 1918. Serial No. 246,971.

To all whom it may concern:

Be it known that I, RUDOLPH BELCHER, a citizen of the United States of America, and a resident of Chicago, county of Cook, and 5 State of Illinois, have invented certain new and useful Improvements in Adjustable Gussets for Envelops, of which the following is a specification.

My invention relates to an adjustable 10 gusset or partition for envelops and has for its object the construction of a partition which may be readily applied to large envelops and which may be manually shifted from place to place so as to divide the envelop 15 into compartments of any desired proportions.

In the drawings—

Figure 1 is a perspective view of an envelop showing the partition in place; 20 Fig. 2 is a section on line 2—2 of Fig. 1; Fig. 3 is an enlarged section on line 3—3 of Fig. 2; and

Fig. 4 is a perspective view of the partition detached.

The envelop E is of the heavy paper type 25 and has the ordinary bellows edges B at its bottoms and ends. It is open above and ordinarily has the rear edge C higher than the front edge D. That difference in height, 30 however, is for other purposes and has nothing to do with the present invention.

The partition P is preferably of the same 35 material as the envelop and is folded as shown in the drawings so that it will have the same bellows action as the edges B.

On one edge of the partition P is a short 40 metal clip F and on the other edge is a long metal clip H. The upper ends of these clips terminate in hooks F' for engaging the edge D and H' for engaging the edge C. These hooks are so made that when the partition is in place they will pinch the edges.

C and D and hold the partition in place by friction on said edges.

The clips F and H have their lower portions bent around the edges of the partition P as shown in Fig. 3, and those clips are held to the edges of the partition by friction. They may, of course, be secured in other ways, but friction is sufficient for the purpose. The connection between the clips and the edges of the partition P is secured by putting them under a press which will make the frictional contact sufficient to withstand any strain less than that enough to tear the paper. The frictional contact between the hooks and the edges of the envelop is, however, much less and only enough to normally prevent the partition from slipping.

The drawings show only one partition in 60 the envelop E. It will be evident, however, that any number of similar partitions may be used in the same envelop, and that the partitions may be manually adjusted to any position.

What I claim is:

1. A partition for envelops consisting of a body P folded as shown, and clips secured to the edges of said body, said clips being provided with hooks adapted to engage and have frictional contact with the edges of the envelop with which the partition is to be used.

2. An adjustable partition for envelops consisting of an expandable body, and clips clamped upon the outer edges of said body, 75 said clips having hooks adapted to engage the upper edges of the front and back of an envelop, and said hooks being arranged to have a light frictional contact with said 80 edges.

Signed at Chicago, Ill., July 24, 1918.

RUDOLPH BELCHER.
